UNITED STATES PATENT OFFICE

2,295,835

TOY SUBMARINE

Erling Wallace Eklof, Minneapolis, Minn.

Application January 11, 1940, Serial No. 313,417

7 Claims. (Cl. 46—94)

My invention relates to toy submarines and has for an object to provide a submarine simulating in performance and appearance an actual submarine.

An object of the invention resides in providing a submarine which will be stable and which will float at the desired depth.

Another object of the invention resides in providing a submarine in which the center of gravity may be readily shifted to procure stability of the submarine.

An object of the invention resides in constructing the submarine with an upper part and a lower part detachably connected together and in providing a compartment within the lower part for the reception of the driving mechanism of the submarine.

Another object of the invention resides in constructing the upper part as a float by means of which buoyancy of the submarine is procured and in constructing the lower part as a metal shell detachably connected to the float and receiving water when the submarine is in use.

A feature of the invention resides in constructing the shell from sheet metal bent to provide a bottom and two sides connected therewith and adapted to engage the float and hold the parts in assembled position.

Another object of the invention resides in providing submerging fins on the shell disposed at the upper edges of the same and bent outwardly therefrom.

A feature of the invention resides in disposing the operating mechanism of the invention within the interior of the shell and below the float.

An object of the invention resides in rotatably mounting in the shell a propeller shaft and in providing an elastic band extending between the propeller shaft and a fastening secured to the float.

A still further object of the invention resides in providing a groove in the underside of the float and a weight movable along said groove and serving as ballast for shifting the center of gravity of the submarine to stabilize the same in the water.

Another object of the invention resides in providing a torpedo expelling device operated by the elastic band.

An object of the invention resides in constructing the torpedo expelling device with a tube having a spring therein and in further providing a catch for holding the spring in retracted position.

An object of the invention resides in providing

5 a threaded member operated by said elastic band in further providing a nut advanced by said threaded member for disengaging said catch from said spring after the submarine has been propelled for a predetermined length of time.

A feature of the invention resides in providing a channel-shaped guide attached to the bottom of the shell and supporting the threaded member and torpedo tube and guiding the nut for movement along the same.

Other objects of the invention reside in the novel combination and arrangement of parts and in the details of construction hereinafter illustrated and/or described.

15 In the drawing:

Fig. 1 is a side elevational view of a toy submarine illustrating an embodiment of my invention.

20 Fig. 2 is a plan view of the structure shown in Fig. 1.

Fig. 3 is an elevational longitudinal sectional view taken on line 3—3 of Fig. 2.

25 Fig. 4 is a view similar to Fig. 3 of a portion of the structure shown therein and drawn to a greater scale.

Fig. 5 is a cross sectional view taken on line 5—5 of Fig. 3.

30 My improved toy submarine comprises a hull which I have indicated in its entirety by the reference numeral 10. This hull consists of an upper portion 11 and a lower portion 12 detachably connected together. The portion 12 of the hull is formed with a compartment 13 within the same in which the operating mechanism of the invention is disposed. These various parts will 35 now be described in detail.

The upper part 11 of the hull 10 is constructed solid and from wood, cork or some other similar suitable buoyant material and serves as a float 40 for supporting the submarine in the water. The major portion of this float is exposed and is shaped as indicated at 14 in Fig. 5 to simulate in appearance the upper portion of a submarine.

The float 11 is formed with a flat bottom 15 allowing a space in the shell for mechanism and to fill with water so as to increase the draft of the submarine to a maximum amount yet keeping the conning tower above water when not submerged. Attached to the uppermost portion of the float 11 is an imitation conning tower 16 which has issuing upwardly from it an imitation periscope 17. Likewise at the rearward portion of the float is provided an imitation hand rail 18 which may be constructed of wire bent in the desired form. These various parts are merely added to the

hull of the submarine for the sake of appearance and have no function in the operation thereof.

The lower part 12 of the hull 10 of the submarine consists of a shell which is constructed from sheet metal bent as shown in Fig. 5 to provide a bottom 19 and sides 21 and 22 extending upwardly therefrom. These sides and the bottom are curved to simulate in appearance the hull of an actual submarine. The sides 21 and 22 project upwardly above the bottom 19 of the float 11 so that the uppermost marginal portions 23 of said sides engage the lowermost portion of the float 11. As will be noted in Fig. 2 both the float 11 and the shell 12 are pointed at their ends and the parts of the shell closely fit the parts of the float so that the assembled structure has the general appearance of a real submarine. The extreme ends 24 and 25 of the shell 12 project beyond the ends 26 and 27 of the float 11 and overlie one another. These ends are secured together by means of ears 28 formed on one of the sides of the shell and bent over upon the other side of the shell.

The ends 24 of the sides 21 and 22 of the shell 12 extend considerably beyond the end 26 of the float 11 and are shaped to form a part 29 which serves as a rudder for the submarine. This part of the shell is notched, as indicated at 31, to form a space in which the propeller of the submarine is disposed.

At the forward ends 25 of the sides 21 and 22 of shell 12 are provided rearwardly extending tongues 32 which are free to flex toward and from each other. These tongues frictionally engage the upper surface of the float 11 and urge the same into the shell 12. To limit such movement a number of stops 33 are provided which, in the particular form of the invention shown, consists of nails driven into the float 11. These nails engage the uppermost edges 34 of the marginal portions 23 of the sides 21 and 22 and limit the movement of the float 11 into the shell 12. The rearward end 26 of the float 11 fits in between the portions of the ends 24 where the same commence to diverge and is thus held in position. The forward end 27 of the float 11 is engaged between the tongues 32 and held in position thereby. In this manner the float is detachably mounted with reference to the shell 12 and may be readily removed therefrom, when desired.

Issuing outwardly from the edges 34 of the sides 21 and 22 of shell 12 are two submerging fins 35 and 36. These fins are integral with the shell and are disposed in co-planar relation extending outwardly from the shell in a substantially horizontal direction. The rearward ends 37 of these fins are detached from the sides 21 and 22 of shell 12 so that the same may be bent upwardly and downwardly. Slight bending of these fins causes the submarine to submerge when the same is suitably propelled and permit of rising of the submarine after the energy of the motor has been spent.

In the bottom 15 of the float 11 is formed a groove 38. A weight 39 constructed of metal is slidably mounted in this groove and may be positioned at any locality along the same. The groove 38 extends from one end of the float 11 to the other. The weight 39 is frictionally held in position within the groove 38 and serves as ballast for procuring stability to the submarine.

Between the ends 24 of the sides 21 and 22 of shell 12 is provided a bearing 39 shown in Fig. 3. In this bearing is journaled a propeller shaft 41

which has rigidly secured to the protruding end thereof a propeller 42 disposed in the space 31 between the rudder 29 and the ends 24 of the shell 12. This propeller has a hole 43 in the end thereof through which a suitable crank may be attached for rotating the shaft 41. The inner end of the shaft 41 has formed on it a hook 44 to which is attached one end of an elastic band 45. The other end of the said elastic band is secured to a fastening 46 on the underside 15 of the float 11 at the forward end 27 thereof. This fastening may be in the nature of a hook which is screwed into the underside of the float 11. It will readily be comprehended that, when the shaft 41 is rotated through the crank attached to the propeller 42 the elastic band 45 is twisted and turns the propeller when the crank is disengaged therefrom and the propeller released.

Within the compartment 13 of the shell 12, and at the forward end of the submarine, is disposed a torpedo tube 47. The forward end 50 of the tube 47 projects outwardly through the shell 12 at the forward portion of the submarine. The said tube has mounted in it a compression coil spring 48 which is seated against the end 49 of said tube and is adapted to engage the rearward end of an imitation wood torpedo 51 received within the tube. The spring 48 is normally retracted and so held by a device to be presently described in detail, and when released strikes the torpedo 51 and ejects the same from the forward end 50 of the tube 47, whereupon the torpedo enters the water and when its initial energy is spent floats to the surface.

Attached to the bottom 19 of the shell 12, of the submarine, is a channel-shaped guide 52 which is constructed with a web 53 and with flanges 54 and 55 extending outwardly therefrom. The web 53 lies along the bottom 19 of the shell 12 and is constructed with ears 56 which extend through suitable apertures in the shell and are bent over to hold the said guide firmly attached to the shell. The forward end of the guide 52 has bent upwardly from it an end wall 57 which is provided with a suitable opening, not shown, which receives the torpedo tube 47. The flanges 54 and 55 of the guide 52 are spaced a distance apart to receive the said torpedo tube which extends through the end wall 57 and into the space between the said flanges. The other end of the guide 52 has bent upwardly from it another end wall 58. In addition to the end wall 58 an ear 59 is struck out of the metal of the bottom 19 of the shell 12 and is bent inwardly into the compartment 13 and lies parallel with the end wall 58. This ear is drilled to form a second bearing for the propeller shaft 41 which projects slightly beyond the said ear.

Rotatably mounted in holes drilled in the ear 59 the end wall 58 and the end wall 57 is a threaded spindle 61. At a locality between the end walls 58 and 59 and attached to the spindle 61 is a spur gear 62. This spur gear meshes with another spur gear 63 attached to the propeller shaft 41. As the propeller shaft 41 rotates the threaded spindle 61 is turned. Mounted on the threaded spindle 61 is a nut 64 which is held from rotation by means of two flanges 54 and 55 of the guide 52. This nut is movable along the said guide upon rotation of the threaded spindle 61 and is adapted to move toward and from the torpedo tube 47.

Pivoted between the two flanges 54 and 55 of the guide 52 is a catch 65 which is adapted to

enter into a hole 66 in the torpedo tube 47 and to engage the spring 48 when the same is urged into retracted position and to so hold the same. This catch has issuing from it a rearwardly extending lever 67 which is disposed between the flanges 54 and 55 of the guide 52. The lever 67 has a cam surface 68 adapted to be engaged by the nut 64. When the said nut engages the cam surface 68, catch 65 is disengaged from the spring 48 and the said spring strikes the torpedo 51 and ejects the same from the torpedo tube 47. The lever 67 has a finger piece 69 formed at the rearward end thereof which projects through a slot 72 formed in the web 53 of the guide 52 and the bottom 19 of the shell 12. By means of this finger piece the catch 65 may be manually operated to permit of inserting the torpedo into the tube 47 and retracting spring 48.

The operation of the invention is as follows: The submarine when placed in water, floats due to the float 11. By reason of the fact that there are openings in the shell so that water enters the compartment 13 and the submarine is caused to float at the desired elevation. Due to the fact that the submarine is constructed with the upper portion thereof as a float and the lower portion constructed out of metal, the center of gravity of the submarine is relatively low and lateral stability of the submarine is brought about. To procure stability in a longitudinal direction the weight 39 is adjusted lengthwise within the groove 38 until the desired results are procured. Prior to use the portions 37 of the fins 35 and 36 are bent downwardly a sufficient amount to cause the submarine to submerge when the propeller is driven. When the submarine is to be used, the elastic band 45 is twisted by applying the crank to the propeller 42. This causes the nut 64 to travel toward the rear of the submarine. The torpedo 51 is next inserted into the torpedo tube 47 and pressed against the spring 48 by means of a pencil or some other suitable instrument. As the said spring compresses, the catch 65 engages the convolutions thereof and holds the spring in retracted position. After the propeller shaft has been wound up a sufficient number of times the crank is removed and the submarine, while the propeller is being held, is lowered into the water. When the propeller is released the same commences to rotate and causes the submarine to travel forwardly. Due to the action of the portions 37 of the fins 35 and 36 the submarine submerges. As the propeller continues to operate the submarine advances beneath the surface of the water and the nut 64 which is threaded on the threaded spindle 61 advances along the guide 52. When the nut 64 engages the cam surface 68 lever 67 is depressed and the catch 65 disengaged from engagement with the spring 48. This ejects the torpedo 51 from the tube 47 and the torpedo is directed into the water. After the energy, imparted to the torpedo, is spent the torpedo floats up to the surface of the water. The submarine then continues to travel under the water until the energy of the elastic member 45 is spent or until the nut 64 engages the end wall 57 and terminates the movement. The submarine then floats up to the surface of the water.

The advantages of my invention are manifest. An extremely simple and practical construction is provided which simulates in appearance and maneuvers that of an actual submarine. The device is extremely stable transversely and sta-

bility longitudinally may also be procured by the adjustment of the adjustable weight provided. By bending the fins of the submarine, submerging is procured when the submarine reaches a predetermined speed. With my invention the torpedo is ejected after a predetermined length of time, subsequent to submerging of the submarine, so that the torpedo becomes visible before the submarine emerges. After

10 the energy of the elastic member is spent the submarine comes to the surface where the same may be retrieved. By constructing the submarine in two parts accessibility is had to the interior and to the operating mechanism within the same.

15 By attaching the elastic member at one end to the propeller shaft and at its other end to the float the said elastic member may be easily assembled before the parts of the submarine are secured together. My invention is extremely attractive in appearance and is fascinating in its performance.

20 Changes in the specific form of my invention, as herein disclosed, may be made within the scope of what is claimed without departing from the spirit of my invention.

25 Having described my invention, what I claim as new and desire to protect by Letters Patent is:

30 1. A toy submarine comprising a hull, the upper portion of which is formed with a float constructed of wood and the lower portion of which is constructed with a sheet metal shell having spaced sides adapted to engage the float, propelling mechanism for the submarine disposed within said shell and beneath said float, and submerging fins bent outwardly from the sides of the shell at the upper edges thereof, portions of said fins being free from the sides of the shell to permit of bending of the same.

35 2. A toy submarine comprising a hull, a propeller carried thereby, a rotary member for operating said propeller, a torpedo expelling device including a spring for expelling the torpedo, a catch for holding said spring compressed, a screw driven by said rotary member, a nut engaged by said screw, and means operated by said nut for disengaging said catch from said spring.

40 3. A toy submarine comprising a hull, the upper portion of which is formed with a float constructed of wood and the lower portion of which is constructed with a sheet metal shell having spaced sides adapted to engage the float, and a bottom connected therewith, a channel-shaped guide disposed within said shell and mounted on said bottom, a torpedo tube at the forward end of said guide, a spring within said torpedo tube, a catch pivoted between the flanges of said guide and engaging said spring for holding the same in retracted position, a screw extending along said guide, a nut threaded on said screw and movable along said guide, means operated by said nut for releasing said catch, and means for rotating said screw.

45 4. A toy submarine comprising a hull constructed with an upper part and a lower part detachably connected together, the upper part being removable from the lower part by movement in an upward and forward direction, a propeller shaft rotatably mounted in the lower part and disposed at the rear end of the hull, a fastening secured at the other end of the upper part and an elastic band extending between said propeller shaft and fastening, and serving to both propel the propeller and hold the parts assembled.

5. A toy submarine comprising a hull, the upper portion of which is formed with a float constructed of wood and the lower portion of which is constructed with a sheet metal shell having spaced sides adapted to engage the float and lying in continuation of the outer surface of the float, submerging fins formed from the upper edges of the sheet metal shell, said fins being bent outwardly from said shell substantially at right angles to the surfaces of said shell and float, and propelling mechanism for the submarine disposed within said shell and beneath said float.

6. A toy submarine comprising a hull, a channel-shaped guide disposed within said hull, a torpedo tube at the forward end of said guide, a spring within said torpedo tube, a catch pivoted

between the flanges of said guide and engaging said spring for holding the same in retracted position, and means extending along said guide for releasing said catch.

5 7. A toy submarine comprising a hull, spaced supporting members carried by said hull, a propeller shaft journaled in one of said supporting members, a screw journaled in both of said supporting members and disposed in proximity to 10 said propeller shaft, gearing between said propeller shaft and screw for rotating said screw, resilient means for turning said propeller shaft and extending parallel with said screw, a torpedo expelling device, and means operated by said 15 screw for actuating said torpedo expelling device.

ERLING WALLACE EKLOF.
